UNITED STATES PATENT OFFICE.

JOSEPH YATES, OF MOTT HAVEN, NEW YORK.

IMPROVEMENT IN APPARATUS FOR THE MANUFACTURE OF IRON.

Specification forming part of Letters Patent No. 41,808, dated March 1, 1864.

To all whom it may concern:

Be it known that I, JOSEPH YATES, of Mott Haven, in the county of Westchester and State of New York, have invented certain new and useful Improvements in the Manufacture of Iron; and I hereby declare that the following is a full, clear, and exact description of the same, reference being had to the accompanying drawings, in which—

Figure 1 is a front elevation of an improved apparatus for making malleable or wrought iron direct from the ore, A in said figure representing a welding-furnace, B a reducing-oven, and C the chimney. Figs. 2 and 3 are two side elevations, and Figs. 4 and 5 are sectional views, of the same according to the lines a-b and c-d in Figs. 5 and 4, respectively.

The process of making iron directly from the ore is well understood in principle. The chemical agents which determine the conversion of the ore and the conditions under which it is effected have also been ascertained, and yet this manufacture is carried on in but few localities, and there in the most primitive manner; and all attempts at introducing this manufacture in localities which do not offer precisely the same conditions of abundance of fuel and ore, and where economy is the *sine quanon* of manufacture, have utterly failed. The numerous experiments which have been instituted from time to time to adapt this process by peculiar construction of apparatus to the ordinary conditions of an iron-producing country have demonstrated that success in this manufacture depends wholly upon the proper application of heat; and the great problem to be solved consists in the construction of a furnace in which the ore and the ingredients used in connection therewith to effect its reduction are exposed to the proper degree of heat, and so that the same shall be perfectly under the control of the operator, enabling him to regulate the same at pleasure and according to circumstances.

In my improved apparatus, consisting of a welding-furnace, a reducing-oven, and a chimney, I have so combined the parts constituting the same that the heat is distributed to effect in each the operation there to be performed.

The first part of my invention has for its particular object so to convey the heated gases from one portion of the apparatus to the other

that the gases or flame shall be expanded in the turning-flues for the purpose of preserving the flues in working order; also, to provide each reducing-chamber with the means of therein regulating the draft or pressure of the gases.

To this end the first part of my invention consists, first, in the employment, in combination with a reducing-oven having two or more reducing-chambers superposed and heated by the flame or gases derived from a welding-furnace, of a double or divided chimney, so that each chamber shall be provided with its own chimney or division of chimney, which may or may not intercommunicate at the pleasure of the operator; secondly, in locating such double or divided chimney back of and in contiguity with the reducing-oven, the opening of communication of the chimney with the oven being arranged in relation to the partition or division walls, so as to allow of the expansion of the gases previous to their entering the reducing-chambers.

The object of the second part of my invention is to secure uniform temperature over and through the whole reducing-table.

To this end the second part of my invention consists in forming the reducing-tables of flat arches made of refractory brick set edgewise, said brick being of uniform width, so that the arch shall be of uniform thickness throughout.

The third part of my invention has for its object so conducting the flame and heated gases to and from the reducing-chamber as that the ore upon the table may be worked while the furnace is in blast and the oven in operation.

To this end the third part of my invention consists, first, in so locating the divided chimney in relation to the reducing-oven as that the flame and heated gases shall be diverted from the working-doors, and, secondly, in combining with a reducing-oven having two laterally-arranged series of reducing-chambers a double or divided chimney located in contiguity with the oven and between the working-doors thereof.

To more fully appreciate the nature of my invention, I shall briefly refer to the process of manufacture, in conformity with which a furnace for making iron directly from the ore is to be constructed.

Iron ore, preferably such in which the oxide of iron is mixed with but little earthy matter

pulverized to a fineness resembling sea-sand, and mixed with from twenty to twenty-five per centum of pulverized charcoal or bituminous coal, is exposed to a certain high degree of temperature in a medium from which free oxygen is carefully excluded. The particles of iron ore thus placed in contact with a material emitting carbureted vapors while exposed to a high temperature will be speedily reduced. The deoxidized metal is then in a state of great division, and disseminated among the earthy matter and the residue of unconsumed coal. To effect the union of these iron particles the mass is exposed to a welding heat, and the particles are caused to agglutinate, to form a ball, together with scoria or earthy matter in fusion, which latter is finally expelled by the action of the squeezer and hammer. The reduction proper is a very delicate operation, and it is upon this stage of the process that failure or success mostly depends.

From the above it will be understood that the temperature at which the reduction is effected is high, yet it is important that it should not be such as to cause the earthy matter mixed with the ore to enter in fusion, because they will have a tendency to retain in their vitreous mass the unreduced oxide of iron, and form a slag rich in iron, and thus be productive of much waste. Now, in an apparatus in which the whole process of making iron directly from the ore is carried on with but one fire, the same flame which is to produce welding heat in one part of the apparatus is also to produce the heat requisite to reduce the ore in another part of the apparatus; hence the necessity of and difficulties in so constructing the apparatus as that the heat shall be duly tempered and regulated.

The reduction of the ore is effected in my improved apparatus in an oven erected on columns at such elevation and position in relation to the welding-furnace or heat-generator as that the heat radiated or otherwise conveyed from the latter shall not injuriously affect the structure of the oven, and that fresh air may surround and freely circulate about the same. The oven is divided into chambers called "reducing-chambers," which are formed, as shown in the accompanying drawings, of flat arches thrown from the exterior side walls, G, to a middle wall, W, common to both. These arches constitute the reducing-tables, and it is upon these tables that the ore and coal mixture is spread while exposed to the action of the heated gases passing over and under the said tables. In former attempts at making iron directly from the ore great difficulty was experienced in constructing these tables. They were generally plane-surfaced, arched underneath, so that the table was thin in the center, of gradually increasing thickness toward its supporting-walls, and the consequence was that the ore was reduced along a middle strip much sooner than upon the other portions of the table, which necessitated constant stirring; but by frequently stir-

ring the mass air was necessarily admitted, which occasioned the reoxidation of metal already deoxidized. By making the tables but slightly arched I am enabled to make them of uniform thickness throughout, and thus to heat them uniformly in all its parts. The tables are made of fire-brick set edgewise, and have a slight inclination to facilitate their discharge. The flue F is extended by an arched wall parallel with the first table, and the flame and gases are conveyed by this flue from under the first table and into first reducing-chamber—i. e., into the space between the first and second tables—by means of two apertures, I J, in the outer wall, K, of the reducing-oven, the one above and the other below the first reducing-table, and both communicating with the interior of a chimney whose top orifice is furnished with a damper, L, so that when closed the gases issuing from under the table not able to escape through the chimney will be compelled to pass into the reducing-chamber above the table. The gases are now forced to pass over the edge M of the upper table, and are caused to travel along its upper surface, finally to issue at the orifice N into a chimney, also provided with a damper.

Instead of having two separate chimneys—one for each reducing-chamber—I use a single chimney divided by a vertical transverse wall—i. e., a wall running across the chimney parallel with the back wall of the oven. This vertical division-wall is supported by an arch, P, which forms a horizontal partition on a level with the upper reducing-table, cutting off direct communication between the two divisions. If a double oven be used, as that shown in the accompanying drawings, the chimney is located in the middle of the back wall of the oven, and is divided by a vertical partition-wall in continuation of that in the reducing-oven, and extending from top to bottom of the chimney. By this arrangement the current, pressure, and temperature of the flame and gases may be regulated. If, for instance, the pressure and temperature be too great, it is simply necessary to ease the valves on top of the chimney, and if for some cause or other it be expedient to divert the current of the gases and discharge without allowing them to enter either chamber, it is only required to open the damper L'. Another advantage due to this arrangement consists in the expansion of gases at that point where by sudden contraction they would be condensed and develop heat, that would soon melt away the flues or orifices for the passage of the gases to and from the chambers. Thus by allowing the gases to expand in the chimney and at the turning-points they will not overheat the narrow flues through which they are forced to pass.

The working-doors through which the operator observes the operation and from time to time stirs the mass, so as to expose all or nearly all the particles to the action of the deoxidizing-flame, and when deoxidized dis-

charges the same from off the tables, are located centrally in relation to the tables, and the position of the chimney and the flues leading into it is so determined as that the gases shall be diverted from the working-door and present no impediment to the operator watching the progress of the work, stirring the mass, and discharging the table when required. In double ovens the chimney is located, as shown in the accompanying drawings, in the middle—that is, between the two working-doors—and is preferably of such width as to allow of the doors being set in the center of each reducing-chamber.

Having fully described by invention and the manner in which the same is or may be carried into effect, I shall state my claims, as follows:

1. The employment, in combination with a reducing-oven having two or more reducing-chambers superposed and heated by the flame or gases derived from a welding-furnace, of a double or divided chimney, so that each chamber shall be provided with its own chimney or division of chimney, which may or may not intercommunicate at the pleasure of the operator, substantially as herein set forth.

2. Locating such double or divided chimney back of and in contiguity with the reducing-

oven, the openings of communication of the chimney with the oven being arranged in relation to the partition or division walls, so as to allow of the expansion of gases previous to their entering the reducing-chambers, substantially as herein set forth.

3. The arched reducing-tables formed of refractory brick of uniform width, set edgewise or otherwise, so that the same shall be of uniform thickness throughout, substantially as set forth.

4. So locating the divided chimney in relation to the reducing-oven as that the flame and heated gases shall be diverted from the working-doors, substantially as herein set forth.

5. Combining with a reducing-oven having two laterally-arranged series of reducing-chambers, a double divided chimney located in contiguity with the oven and between the working-doors thereof, substantially as herein set forth.

In testimony whereof I have signed my name to this specification before two subscribing witnesses.

JOSEPH YATES.
